FISH LURE

Charles P. Helin, Grosse Pointe Park, Mich.
(4099 Beaufait, Detroit, Mich.)

Filed Jan. 29, 1960, Ser. No. 59,205

Term of patent 14 years

(Cl. D31—4)

FIG. 1 is a front perspective view taken from the bottom and left side of a fish lure embodying my new design.

FIG. 2 is a rear perspective view taken from the top and right side thereof.

FIG. 3 is a bottom plan view.

FIG. 4 is a top plan view.

FIG. 5 is a right side elevational view thereof.

FIG. 6 is a sectional view taken along the line 6—6 in FIG. 5.

FIG. 7 is a sectional view taken along the line 7—7 in FIG. 5.

FIG. 8 is a vertical sectional view taken along the line 8—8 in FIG. 4.

The broken line representations in FIG. 1 are for illustrative purposes only.

I claim:

The ornamental design for a fish lure, as shown and described.
